CLAIM

I claim the ornamental design for a propeller through-hole, as shown and described.

DESCRIPTION

FIG. 1 is a perspective view of a propeller through-hole showing my new design;

FIG. 2 is a top view of the propeller through-hole of FIG. 1; FIG. 3 is a bottom view of the propeller through-hole of FIG. 1;

FIG. 4 is a left side view of the propeller through-hole of FIG. 1;

FIG. 5 is a right side view of the propeller through-hole of FIG. 1;

FIG. 6 is a front side view of the propeller through-hole of FIG. 1;

FIG. 7 is a rear side view of the propeller through-hole of FIG. 1; and,

FIG. 8 is a partially assembled view of the propeller through-hole of FIG. 1 inserted with a propeller through-hole insert.

The broken lines are for the purpose of showing environmental structure, and form no part of the claimed design.
